UNITED STATES PATENT OFFICE.

JAMES GAYLEY, OF NEW YORK, N. Y.

APPARATUS FOR DRYING AIR BY REFRIGERATION.

1,002,576.

Specification of Letters Patent. Patented Sept. 5, 1911.

Application filed January 14, 1909. Serial No. 472,277.

To all whom it may concern:

Be it known that I, JAMES GAYLEY, of New York, in the county of New York and State of New York, have invented a new and useful Apparatus for Drying Air by Refrigeration, of which the following is a full, clear, and exact description, reference being had to the accompanying drawings, forming part of this specification, in 10 which—

Figure 1 is a plan view of a refrigerating building constructed in accordance with my invention; Fig. 2 is a sectional side elevation of the same; Fig. 3 is a partial vertical section showing a system of baffle plates; Figs. 4 and 5 are views similar to Fig. 3, showing modified arrangements of baffle plates and Fig. 6 is a general view showing the spray devices.

20 My invention relates to the drying of air by refrigeration in accordance with the well known system of my prior patents, and is designed to economize in the cost of operation by forcing the air into closer contact 25 with the cooling pipes, and at the same time insure the flowing of the thawing water over the cooling pipes in removing the congealed moisture therefrom. In this system of drying air, one of the difficulties encountered is 30 the uneven distribution of the air flowing up through the chambers, as it tends to flow in larger quantities along the side walls and thus avoid the proper contact with the cooling pipes. Furthermore, in thawing the 35 congealed moisture from the pipes, this water tends to flow along the side walls out of contact with the pipes, thus requiring a larger amount of water to be used, and tending to impart heat to the refrigerating 40 chamber which reduces the economy and requires a longer time in getting the chamber in working condition.

45 My invention overcomes or reduces these difficulties and consists in applying baffles to the walls of the chamber or chambers, these baffles or deflectors forcing the air into more intimate contact with the pipes and also directing the thawing water into contact with these pipes.

50 In the drawing I show a refrigerating building 2, having a series of refrigerating chambers 3. The brine or refrigerating agent for cooling the air passes through pipe coils 4, arranged in the chamber. In Fig. 3, 55 I show the chambers as divided by brick or concrete walls 5, which walls are provided

with baffle plates 6, which project toward the coils and are preferably of steel or other metal. These may be located at any desirable distances apart and may project to 60 any desired amount. In Fig. 4 I show a double plate wall 7, which is filled in with non-conducting material and with angle iron baffle plates 8, riveted or otherwise secured thereto. In Fig. 5 I show a form of brick 65 or concrete wall 9, provided with integral built in deflectors 10. In all the forms, the baffle plates, deflectors, or distributors prevent the rising air from "channeling" up 70 along the walls and force this air into intimate contact with the cooling pipes. Moreover, in the spraying of the pipes by spraying the nozzles of the upper part of the chambers, the water or thawing liquid as it descends through the chambers will be 75 directed away from the walls and upon the pipes, thus reducing the amount of water and consequently the heating of the chamber.

The advantages of my invention result 80 from the use of the deflectors or distributors, which cause a more intimate contact of the air with the cold pipe surfaces, and also direct the thawing water away from the walls 85 and over these pipes.

Many variations may be made in the form and arrangement of the chambers, cooling pipes, baffle plates or distributors, etc., without departing from my invention.

I claim:

1. In an apparatus for drying air by refrigeration, a chamber containing a series of vertical rows of cooling pipes, the rows nearest the side walls being spaced apart therefrom, said chamber having deflectors 95 or baffles extending from the walls inwardly to but not beyond the adjacent pipes arranged to direct the air among the coils, substantially as described.

2. In an apparatus for drying air by refrigeration, a chamber containing a series of vertical rows of refrigerating pipes, the rows nearest the walls being spaced apart therefrom, the walls of the chamber having projecting baffles or deflectors terminating 100 at or near the adjacent pipes, substantially as described.

3. In apparatus for drying air by refrigeration, a chamber having a series of vertical rows of cooling pipes, the rows 110 nearest the side walls being spaced apart therefrom, means for directing air through

the chamber, and baffles or deflectors arranged to direct the air away from the walls and among the pipes, said baffles terminating at or near the pipes adjacent to the walls, 5 substantially as described.

4. In apparatus for drying air by refrigeration, a chamber having a series of vertical rows of refrigerating pipes, the rows nearest the walls being spaced apart therefrom, spray pipes arranged to direct thawing liquid over the refrigerating pipes, the walls of the chamber having deflectors arranged to direct the thawing liquid into contact with the pipes, said baffles terminating at or near the pipes adjacent to the walls, 15 substantially as described.
5. In apparatus for drying air by re-

frigeration, a cooling chamber having a series of refrigerating pipes therein, the pipes nearest the side walls being spaced 20 apart from said walls, the opposite side walls having deflectors extending toward the nearest pipes and terminating at or adjacent thereto to allow a straight upward flow of the air while preventing it from 25 "channeling" along the side walls, substantially as described.

In testimony whereof, I have hereunto set my hand.

JAMES GAYLEY.
